UNITED STATES PATENT OFFICE.

SAMUEL H. COHEN, OF LOS ANGELES, CALIFORNIA, ASSIGNOR, BY MESNE ASSIGNMENTS, TO JERRY-J., INC., OF LOS ANGELES, CALIFORNIA, A CORPORATION OF CALIFORNIA.

ATTACHMENT FOR SWEATERS AND THE LIKE.

Application filed May 6, 1925. Serial No. 28,416.

My invention relates to and has for its purpose the provision of a simple and inexpensive attachment which can be readily applied to sweaters and similarly knitted garments to maintain their normal form or contour so as to prevent stretching and subsequent distortion of the sweater.

My invention is particularly adapted, although not necessarily, for sweaters of the slip-on type, wherein a neck opening is provided by which the sweater can be applied to the body. In this adaptation of my invention, it operates to maintain the original form of the neck opening yet allowing temporary expansion or stretching of the opening to permit of the ready application of the sweater to the wearer. Further, my attachment includes elastic means connecting the shoulder seams of the sweater with the neck opening so as to prevent stretching of the sweater at the shoulder portions and thereby maintaining the original form of the sweater.

I will describe only one form of sweater and one form of attachment embodying my invention, and will then point out the novel features thereof in claim.

In the accompanying drawings

Figure 1 is a view showing in front elevation a conventional form of slip-on sweater having applied thereto one form of attachment embodying my invention.

Figures 2 and 3 are fragmentary sectional views taken on the line 2-2 and 3-3, respectively, of Figure 1.

Referring specifically to the drawings, in which similar reference characters refer to similar parts in each of the views, my invention in its present embodiment is shown applied to a knitted sweater having a V-shaped opening 15 through which the neck and head of the wearer are adapted to be projected when the sweater is in applied position. The sweater is so constructed that shoulder seams 16 are provided which extend from opposite edges of the neck opening downwardly to the sleeves of the garment.

The attachment forming the subject matter of my invention comprises a strip of elastic tape 17 secured by stitching to the inner side of the marginal edge of the wall of the neck opening 15, the tape as so applied describing a figure of the same contour as the opening. By virtue of the fact that

the tape is formed of elastic material, it will be manifest that it operates to maintain the original form of the neck opening yet allowing expansion or stretching of the neck opening in order to permit the projection of the wearer's head therethrough, but as soon as the sweater is in proper position on the wearer, the elastic tape will contract to its normal form thus restoring the original form of the neck opening.

My invention also includes two strips of elastic tape 18 and 19 which as illustrated to advantage in Figure 3 are secured to the inner side of the sweater and in spanning relation to the shoulder seams 16, such strips being co-extensive in length with the shoulder seams in order to re-inforce the latter throughout the length. As these two lengths of tape are formed of elastic material, it will be clear that they will not interfere with that stretching of the shoulder portions of the garment necessary in applying the garment to the wearer, but as soon as the garment has been applied the elastic strips of tape will automatically function to restore the shoulder portions to their normal positions. Experiment has proven that the greatest distortion of the upper portion of a knitted sweater is due to the stretching of the shoulder portions as a result of applying the sleeve portions to the arms of the wearer, as when inserting the arms into the sleeves, a longitudinal stretching of the sleeves takes place which operates directly on the shoulder portions of the garment thereby distorting the normal and symmetrical contour of the sweater. The elastic strips of tape yield to this stretching when inserting the arms within the sleeves but immediately contract the knitted fabric to its normal form as soon as the arms have been completely inserted into the sleeves.

Although I have herein shown and described only one form of attachment for sweaters and the like embodying my invention, it is to be understood that various changes and modifications may be made therein without departing from the spirit of the invention and the spirit and scope of the appended claim.

What I claim is:

The combination with a sweater having a single opening at its neck portion, of a strip of elastic tape surrounding said open-

ing and secured to the inner face of the sweater, and a plurality of elastic tapes secured to the inner face of the sweater and extending along the lines of both shoulders and terminating at their outer ends at the junction of the sleeves of the sweater with the shoulder portions thereof and at their inner ends adjacent to the neck portion of the sweater, all of said strips functioning to exert an elastic influence upon the fabric of the sweater, whereby the neck portion is made to closely adapt itself to the neck of the wearer and the shoulder portions to the shoulders of the wearer. 10

SAMUEL H. COHEN.
